UNITED STATES PATENT OFFICE.

JOSEPH H. FULTON, OF WEST LEBANON, ASSIGNOR OF TWO-FIFTHS TO
WILLIAM R. HAMILTON, OF INDIANA, PENNSYLVANIA.

CHURN-DASHER.

SPECIFICATION forming part of Letters Patent No. 513,041, dated January 16, 1894.

Application filed June 15, 1893. Serial No. 477,675. (No model.)

To all whom it may concern:

Be it known that I, JOSEPH H. FULTON, a citizen of the United States of America, residing at West Lebanon, in the county of Indiana and State of Pennsylvania, have invented certain new and useful Improvements in Churn-Dashers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in churn-dashers; and it consists in providing the upper end of the dasher-staff with a sleeve which is mounted thereon so that said dasher-staff can rotate or be rigidly connected thereto, for the purpose to be hereinafter set forth; to the lower end of the dasher-staff being attached the blades and a conical sleeve or ferrule.

In the accompanying drawings, forming part of this specification, Figure 1 is a perspective view of a churn-dasher constructed in accordance with my improvements, and Fig. 2 is a side view of the upper part of the dasher-staff, partly in section.

A designates the dasher-staff the upper part of which is reduced to present a portion B of less diameter than the other part of the staff and circular bearing surfaces b and b'. In the upper end of the dasher-staff is an aperture which is threaded to receive the thumb-screw d.

C designates a sleeve which is adapted to fit loosely over the portions b and b' of the dasher-staff and is held thereon by the thumb-screw d, a washer being placed between the head of the thumb-screw and end of the sleeve.

E designates the dasher the blades of which are secured to the lower end of the staff at right angles with each other. The parts of each blade beyond the staff are cut away on

opposite sides, as shown, to provide oblique surfaces g g while the edges h h are slightly beveled.

G designates a conical sleeve or ferrule which is secured to the lower end of the dasher-staff immediately above the blades. The object of this conical sleeve or ferrule is to part the cream and force it out upon the oblique faces of the blades.

In operation, the thumb-screw is loosened, and the operator grasps the sleeve and forces the dasher down, which movement will not turn said dasher as the under side of the blades are flat, but on the upstroke the blades will be revolved on account of the oblique upper surfaces thereof, the dasher-staff revolving within the sleeve. After the cream has been sufficiently churned the thumb-screw can be turned to rigidly connect the sleeve to the dasher-staff, thus making a rigid dasher to use in gathering the butter.

Having thus described my invention, what I claim as new, and desire to secure by Letters Patent, is—

1. In combination with a dasher-staff A having a reduced upper end to provide bearing surfaces b and b' and a dasher rigidly secured thereto, of a sleeve carried by the upper end of the staff, and means substantially as shown for rigidly connecting the sleeve and staff.

2. In combination with a dasher-staff and dasher, the upper end of the dasher-staff having a thumb-screw and washer, a sleeve C mounted on the upper part of the dasher-staff, and held thereon by the thumb-screw and washer, the dasher staff having a reduced portion B to provide bearing surfaces b and b', substantially as shown, and for the purpose set forth.

In testimony whereof I affix my signature in presence of two witnesses.

JOSEPH H. FULTON.
